UNITED STATES PATENT OFFICE.

FRANK M. BUCKMASTER, OF LOWELL, WASHINGTON.

ATTACHMENT FOR HAIR CLIPPERS.

Application filed May 14, 1923. Serial No. 639,001.

This invention relates to attachments for hair clippers of the hand or power driven type, and has for its principal object to provide a heel plate of novel construction that may be detachably secured to the underside of the stationary cutter blade of a pair of clippers, and which has combing teeth extended beyond the clipper teeth that will perform a combing action in the hair as the clippers are advanced and will thereby enable the operator to so shade the cut that no line of demarcation between long and short cuts will be left.

Other objects of the invention reside in the various details of construction of the plate and in the relation it bears to the teeth of the clippers to which it is applied.

In accomplishing these and other objects of the invention, I have provided the improved details of construction, the preferred forms of which are illustrated in the accompanying drawings, wherein—

Figure 1 is a perspective view of a pair of hair clippers to which a combing heel plate, embodying the present invention, is applied.

Figure 2 is a perspective view of the plate removed from the clippers.

Referring more in detail to the drawings—

1 designates a pair of hair clippers, comprising a handle portion 2 to which is fixed a stationary cutter blade 3 upon which a movable blade 4 is reciprocally mounted; this being held in position by means of an overlying clamping plate 5 secured to the handle by means of a set screw 6.

The attachment, embodied by the present invention, consists of a light, resilient plate 7, of metal, or other suitable material, that may be attached to the underside of the stationary cutter blade 3 by means of upwardly and inwardly turned flanges 8 at its opposite side edges, which form inwardly opening recesses wherein the opposite side edges of the blade 3 are received. The plate is of a resilient character and is curved downwardly and rearwardly from its forward edge so that it is in spaced relation to the blade 3, and is held firmly in position by means of its upturned rearward edge portion 9 which engages the base portion of blade 3.

The plate is substantially the same width and length as the cutter blade 3 and covers it completely so as to provide a jointless surface that will slide smoothly over the hair and skin, and to prevent its having too great a tendency to slip, it is provided with forwardly directed corrugations 10.

At its forward edge the plate 7 is provided with regularly spaced teeth 11 forming intermediate, V-shaped, recesses 12. These teeth extend approximately one-fourth inch beyond the clipper teeth and are of such width that there is one for every two teeth of the clipper blades. Preferably, the teeth of the plate would be no thicker than those of clippers as the thinner they are, the better they function when the device is in use.

With the plate so constructed and applied, the teeth thereof act as a comb when the clippers are advanced, thereby enabling the operator to regulate the length of the cut 73 and at the same time to shade the cut in such manner that no line of demarcation between the long and short cut is left by the clipper, thus eliminating the time that is usually required in the tedious operation of going over the cut with comb and shears to smooth down and remove the marks which are usually left where the clipper cuts cease.

Having thus described my invention, what I claim as new therein, and desire to secure by Letters Patent, is:

The combination with a hair clipping device of the character described, of a plate of flexible metal applicable to the underside of the clipping device and having attaching flanges at its opposite edges, said plate being longitudinally grooved so that its central portion is spaced from the base of the clipping device and having an upturned rearward end adapted to engage with the base of the cutter and having its forward end portion longitudinally corrugated with teeth at the forward ends of the corrugations extended forwardly of the teeth of the cutting device.

Signed at Everett, Snohomish County, Washington, this 4th day of May, 1923.

FRANK M. BUCKMASTER.
